CLAIM

The ornamental design for a shelf bracket, as shown and described.

DESCRIPTION

FIG. 1 is a top perspective view of a shelf bracket, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The shelf bracket is shown with a symbolic break in its length. The appearance of any portion of the article between the break lines forms no part of the claimed design. The broken lines in the drawings illustrate portions of the shelf bracket which form no part of the claimed design.
